UNITED STATES PATENT OFFICE.

FRANKLIN D. CUMMER, OF CLEVELAND, OHIO.

GOVERNOR.

SPECIFICATION forming part of Letters Patent No. 309,135, dated December 9, 1884.

Application filed January 23, 1884. (No model.)

To all whom it may concern:

Be it known that I, FRANKLIN D. CUMMER, of Cleveland, in the county of Cuyahoga and State of Ohio, have invented certain new and useful Improvements in Governors; and I do hereby declare the following to be a full, clear, and exact description of the invention, such as will enable others skilled in the art to which it pertains to make and use the same.

10 My invention relates to improvements in that class of governors that have flying weights.

The object of my invention is to provide a single spring that will furnish such centripetal force as may be required in counteracting the 15 centrifugal force of all of the flying weights, and so arranged that the spring will exert the same force on each weight. A further object is to provide convenient mechanism for adjusting the spring so that the engine may be 20 governed at any normal speed that is required.

With these objects in view my invention consists in certain features of construction and in combination of parts hereinafter described, and pointed out in the claims.

25 Heretofore where springs were used on this class of governors a separate spring was provided to operate each weight. It was found impracticable to construct springs of such equal temper, elasticity, and force, and to so nicely 30 adjust the tension of each that the weights in all parts of their respective throw would be acted upon alike by their respective springs. If an equal adjustment of the spring could be made, there would be no assurance that the 35 elasticity and tension of the different springs would remove the same or would change alike. I have therefore invented mechanism by means of which one spring furnishes the centripetal force and operates alike on all of the 40 weights under all circumstances.

In the accompanying drawings, Figure 1 is a vertical section of my improved governor. Fig. 2 is a side elevation of the casing and some of the attachments, with a portion of the 45 casing broken away to show one of the weights.

The shaft, &c., are shown in cross-section.

A represents a hollow shaft provided with the eccentric *a*, that operates the main valve. The shaft is journaled in the boxes *b* and *c*, the former attached to engine-guider *B* and the latter supported by the standard *C*.

D is a sleeve journaled on the shaft *A* and

provided with the eccentric *d*, that operates the cut-off valve.

E is an annular case, attached to the shaft *A*, 55 in which are secured and operated the flying weights *E'*. These weights are pivotally attached at *e*' to the case, and their free ends are respectively connected by the rods *e* to opposite sides of the sleeve *D*, so that every change 60 of the weights in their radial distance from the shaft will slightly turn the sleeve on the shaft and vary the relative positions of the eccentric *d*. The position of the parts is such that when the weights fly outward, the sleeve *D* and the 65 eccentric *d* are turned in the direction that cuts off steam sooner from the engine, and when the weights are drawn inward the said sleeve and eccentric are turned in the opposite direction and admit more steam to the 70 engine. The rods *e*' are at one end pivotally attached to the central portion of the weights, and at the other end are pivotally attached to one end of the bell-crank *F*. These rods are preferably made adjustable in length by means, 75 for instance, of a turn-buckle or other suitable device, and should have universal joints at each end to accommodate themselves to the motion of the weight and bell-crank, that move in planes that are at right angles to each other. 80 The bell-crank *F* are fulcrumed at *f*, and at their inner ends are connected by the links *g* to the equalizing-beam *G*. At the center of this beam is a notch that engages the "knife-edge" of the hook *h*, that is attached to the end 85 of the spring *H*. To the other end of the spring is secured the sliding block *I*, that is an easy fit in the bore of the shaft *A*. This block has a central hole threaded and forming a nut for the screw-rod *J*. This rod is journaled in the cup *k*, that is secured to the end 90 of the shaft. The outer end of the rod *J* should be provided with a band-wheel or some convenient device for turning the rod.

L is the gear by which the shaft *A* is driven. 95

In operating the device when the rod *J* is turned so as to draw the nut *I* in the position shown to the right hand, the tension of the spring is increased, and by means of the connections just described draws the weights toward the shaft, or exerts a centripetal force upon them, and this force may be increased or diminished at pleasure by turning the screw-rod *J* in one direction or the other.

It is evident that whatever force is exerted by the spring will be equally distributed to the two weights; also, when the tension of the spring is increased, the weights are drawn with greater force toward the center and to cause the weights to fly outward in opposition to such increased resistance, it is necessary to increase the centrifugal force by increasing the speed of the shaft until the centrifugal force of the weights overcomes the centripetal force exerted by the spring. It will be seen, therefore, that the normal speed of the engine may be regulated at pleasure by adjusting the tension of the spring.

I do not limit myself to governors whose weights revolve in a vertical plane, as my invention is equally applicable to governors whose weights revolve in a horizontal or an inclined plane.

What I claim is—

1. The combination, with a shaft and an eccentric loosely journaled thereon, of flying weights connected to the shaft, a spring connected by links and levers to the weights and exerting a centripetal force thereon, and links connecting the eccentric and weights, substantially as set forth.

2. The combination, with a tubular shaft and an eccentric loosely journaled thereon, of

a shell or case secured to said shaft, weights pivoted within the case and connected to the eccentric by links, a spring located within the shaft, and devices connecting the weights and spring, all of the above parts combined substantially as and for the purpose set forth.

3. The combination, with a tubular shaft and an eccentric loosely journaled thereon, of a case secured to the shaft, weights pivoted within the case and connected to the eccentric by links, a spring located within the shaft and connected indirectly to the weights, and devices for adjusting the tension of the spring.

4. The combination, with a tubular shaft and an eccentric loosely journaled thereon, of a case secured to the shaft, weights pivoted within the shell and connected to the weights by links, a spring located within the shaft, and adjustable devices connecting the weights and spring, all of the above parts combined, substantially as set forth.

In testimony whereof I sign this specification, in the presence of two witnesses, this 12th day of January, 1884.

FRANKLIN D. CUMMER.
